REDUCTION OF AROMATIC NITROGEN COMPOUNDS

Allen Walter Sogn, Williamsville, N. Y., assignor to Allied Chemical & Dye Corporation, New York, N. Y., a corporation of New York

No Drawing. Application August 6, 1954,
Serial No. 448,377

19 Claims. (Cl. 260—569)

This invention relates to improvements in the reduction of aromatic nitrogen compounds containing nitrogen in a reducible form as a substituent of a benzene nucleus (that is, as a substituent of a hydrogen atom forming part of a benzene nucleus) and at a higher stage of oxidation than the hydrazo stage. It relates more particularly to improvements in the methods of reducing such aromatic nitrogen compounds by means of reducing sugars in alkaline media, and especially aromatic azoxy and azo compounds, for the production of hydrazo compounds and reduction products of intermediate stages of oxidation. A particular feature of the present invention relates to an improved process for the reduction of such aromatic nitrogen compounds which also contain as a nuclear substituent at least one labile halogen atom, and particularly a labile chlorine atom.

The primary object of the present invention is to provide an improved method of carrying out the reduction of aromatic nitrogen compounds of the type referred to above by means of reducing sugars and caustic alkalis.

Further objects of the present invention are to provide improvements in reduction of water-insoluble aromatic nitrogen compounds containing nitrogen in a reducible form as a substituent of a benzene nucleus at a stage of oxidation higher than the hydrazo stage but lower than the nitro stage, whereby the production of azo and hydrazo compounds is effected under mild reaction conditions and the production of primary amines is repressed; to provide improvements in reductions of said type whereby the reducing power of reducing sugars and caustic alkalis, and especially of dextrose and sodium hydroxide, is enhanced and other advantages are secured; and to provide a process for the production of aromatic hydrazo compounds by reduction of aromatic nitro compounds and other reducible aromatic nitrogen compounds with reducing sugars and caustic alkalis under moderate conditions and in simple apparatus.

Another object of the present invention is to provide an improved method for the reduction of aromatic nitrogen compounds containing nitrogen in a reducible form as a substituent of a benzene nucleus at a higher stage of oxidation than the hydrazo stage, especially azoxy and azo compounds of said type, and further containing as a substituent at least one labile halogen atom, especially a labile chlorine atom.

A specific object of the present invention is to provide an improved process for the alkaline reduction of mononuclear aromatic mononitro compounds containing halogen, and especially chlorine, as a nuclear substituent ortho to the nitro group, and especially ortho-chloro-nitrobenzene and reduction products thereof.

2

Additional objects in part will be obvious and in part will appear hereinafter.

The reduction of aromatic nitrogen compounds of the above type for the production of aromatic hydrazo compounds, particularly in connection with the manufacture of benzidine and related diamino-biphenyl compounds, presents a number of problems in view of the nature of said compounds and the intermediate products formed. Unless precautions are taken, the reduction products are mainly aniline or other primary amines, and/or large quantities of hydrogen are evolved.

Thus, under acid conditions, the products are mainly primary amines. Alkaline reducing agents, such as alkali metal alcoholates, ordinarily are not sufficiently effective reducing agents to carry the reduction beyond the azoxy stage unless high temperatures and pressures are employed. Dextrose and caustic alkalis are inefficient; they lead to formation of amines and other by-products and ordinarily are not sufficiently effective to carry the reduction of the nitro compounds substantially beyond the azoxy stage. Zinc, commonly employed with caustic alkalis, is expensive and requires additional processing operations to effect removal of the zinc oxide formed as a by-product.

The reduction of reducible aromatic nitrogen-containing compounds having a labile halogen (e. g. chloro) substituent presents a special problem owing to the reactivity of the labile halogen atom. While it was known to reduce other aromatic nitrogen compounds to azoxy compounds by heating with metal alcoholates in strongly alkaline media, such reducing agents cannot be employed economically for the reduction of reducible aromatic nitrogen compounds containing a labile halogen substituent because the halogen atom reacts with the metal alcoholate to form ethers. Therefore, the reduction of ortho-halogen nitro aromatic compounds and similar reducible aromatic nitrogen compounds having a labile halogen atom as a substituent, as well as the corresponding azoxy and azo compounds, has been carried out by means of zinc and caustic alkali or similar reducing agents. For example, U. S. Patent 2,383,134 describes a process in which a nitro compound is reduced to the azoxy stage by means of dextrose and sodium hydroxide and then further reduced to the hydrazo stage by means of zinc and sodium hydroxide.

According to one feature of the present invention, the reduction of reducible aromatic nitrogen compounds of the above type by means of a reducing sugar and a caustic alkali is carried out in a reaction medium in which a naphthoquinoid reduction promoter has been incorporated. I have discovered that the inclusion of a naphthoquinoid reduction promoter in the reaction mixture has a modifying effect upon the reducing action of the reducing sugar whereby a number of benefits are secured. Thus I have found that the reducing power of reducing sugar-caustic alkali reducing agents is increased materially, the reduction of reducible aromatic nitrogen compounds of the above type proceeds more rapidly, under milder reaction conditions and/or to a higher stage of reduction, than in the absence of the naphthoquinoid reduction promoter.

According to another feature of the present invention, the reduction of aromatic nitrogen compounds of the aforesaid type, wherein the nitrogen is at a higher stage of oxidation than the hydrazo stage but not higher than

the azoxy stage, by means of a reducing sugar and caustic alkali is carried out in a reaction medium which contains a water-miscible organic solvent, more particularly a lower monohydric alcohol (such as methanol, ethanol, or a propanol), and especially methanol. I have discovered, when the reduction of aromatic nitrogen compounds of such type, and especially aromatic azo compounds of such type, by means of a reducing sugar and a caustic alkali is carried out in such a reaction medium, it becomes feasible to produce hydrazobenzenes from azoxy- and azobenzenes by means of caustic alkali-reducing sugar reducing agents.

According to the preferred embodiment of the present invention, and especially for the efficient production of reduction products of a lower stage of oxidation (greater stage of reduction) than the azoxy stage under ordinary temperature and pressure conditions, the reduction of the reducible aromatic nitrogen compound by means of a reducing sugar and a caustic alkali (especially dextrose and sodium hydroxide) is carried out in a reaction medium in which one or more naphthoquinoid reduction promoters have been incorporated, preferably in small amount, and which contains a water-miscible organic solvent, especially a lower monohydric alcohol, and preferably methanol.

I have discovered that the inclusion in the reaction mixture of both a water-miscible organic solvent, such as a lower alcohol, and a naphthoquinoid reduction promoter makes possible the obtainment of higher yields of the desired azoxy, azo and/or hydrazo compounds with less formation of undesired by-products and with the use of much less reducing sugar, as compared with similar reductions carried out in their absence. The reduction can be carried completely through to the hydrazo stage without requiring drastic reaction conditions of temperature and pressure. Even when a lower alcohol is employed as the solvent, the reaction can be carried out so rapidly and under such mild reaction conditions that the main reducing effect is brought about by the reducing sugar rather than by the alcohol. Furthermore, when the reducible aromatic nitrogen compound contains a labile halogen substituent, little ether formation occurs under the mild reaction conditions at which the reduction takes place, notwithstanding the presence of the alcohol and caustic alkali.

The class of naphthoquinoid reduction promoters employed in the practice of the present invention includes all of the various naphthoquinones, derivatives, and related compounds which are effective as reduction promoters in the reduction of said aromatic nitrogen compounds by alcoholic caustic alkali, specifically sodium methylate.

As disclosed in my Patent No. 2,645,636, the addition of naphthoquinones or various derivatives thereof to the reaction medium, in the reduction of reducible aromatic nitrogen compounds of the type referred to above by the action of metal alcoholates, especially alkali metal alcoholates and particularly a sodium methylate reaction medium resulting from the reaction of sodium hydroxide and methanol, exerts a beneficial promoting effect upon the reaction whereby the reaction is accelerated and/or the reduction can be carried to a higher stage of reduction without requiring drastic operating conditions, and other benefits are secured. As disclosed in said patent, various naphthoquinones, and especially 1,4-naphthoquinones, and various derivatives thereof exert this beneficial reduction promoting effect; including substituted naphthoquinones (such as, those in which one or more of the hydrogen atoms of the naphthoquinone nucleus are substituted by another atom or radical), addition compounds of such naphthoquinones (such as, with bisulfites and heavy metal salts), functional derivatives of such naphthoquinones (for example, imides, oximes, semicarbazones and hydrazones), and tautomers and isomers capable of isomerizing to such naphtho-

quinones. Specific illustrative compounds of said type are: 1,4-naphthoquinone, 1,2-naphthoquinone, 2,3-dichloro-1,4-naphthoquinone, 2-methyl-1,4-naphthoquinone, 2-anilino-1,4-naphthoquinone, 2-hydroxy-1,4-naphthoquinone, 1,4-naphthoquinone-2-sulfonic acid, 1,4-naphthoquinone oxime, and the sodium bisulfite addition product of 1,4-naphthoquinone.

I have also found that certain of such derivatives are especially effective as reduction promoters for such reductions, namely, condensed nuclear substitution derivatives of naphthoquinones in which a heterocyclic nucleus is condensed with the quinone nucleus of the naphthoquinone through two adjacent carbon atoms of said nucleus, and especially, 1,4-naphthoquinone-furans and -thiophurans (for example, dinaphtho(2,1,2',3')furan-8,13-dione, dinaphtho(1,2,2',3')furan-7,12-dione, naphtho(2,3-b)furan-4,9-dione, benzo(b)naphtho(2,3-d)furan-6,11-dione, benzo(b)thiophanthrene-6,11-dione, 8-chlorobenzo(b)thiophanthrene-6,11-dione, 3-hydroxybenzo(b)naphtho(2,3-d)furan-6,11-dione, 8,13-diacetoxynaphtho(2,1,2',3')furan, 3-methoxydinaphtho(2,1,2',3')furan-8,13-dione, dinaphtho(1,2,2',3')furan-7,12-dione-5-sulfonic acid, dinaphtho(2,3,2',3')furan-5,7,12,13-tetrone, dinaphtho(2,1,2',3')thiophene-8,13-dione, 5-chlorodinaphtho(1,2,2',3')furan-7,12-diol), as disclosed in my application Serial No. 522,164, filed July 14, 1953.

Furthermore, as disclosed in my Patent No. 2,684,358, this reduction promoting effect upon the reducing action of alkali metal alcoholates on reducible aromatic nitrogen compounds of the type referred to above is also brought about by quinoid hydroxynaphthalene compounds; namely, hydroxynaphthalenes having a total of at least two nuclear substituents of which not more than two are hydroxyl groups and of which substituents two are in the same benzene ring of the naphthalene nucleus in quinoid relation to each other, one of said substituents in quinoid relation being a hydroxyl group and the other of said substituents in quinoid relation being a hydroxyl group or an amine radical, functional derivatives of such compounds, and substituted derivatives of such compounds (for example, 1,4-dihydroxy-naphthalene, 1,4-dihydroxynaphthalene-2-sulfonic acid, 4-amino-1-hydroxynaphthalene, 4-amino-1-hydroxynaphthalene-2-sulfonic acid, 2-amino-1-hydroxynaphthalene, 2,3-dihydroxynaphthalene, 2,3-dihydroxynaphthalene-6-sulfonic acid, 1-amino-2-hydroxynaphthalene, 1-amino-2-hydroxynaphthalene-4-sulfonic acid, 4-phenylamino-1-hydroxynaphthalene).

And, as disclosed in application Serial No. 290,089, filed May 26, 1952, by Francis W. Cashion, a special class of naphthoquinone addition products particularly useful for promoting the reducing action of alkali metal alcoholates on said reducible aromatic nitrogen compounds are the addition products of naphthoquinones with sulfiding compounds; such as, hydrogen sulfide, monosulfides, hydrosulfides, polysulfides, thiosulfates, thiocarbonates, hydrosulfites, thiocyanates and related compounds which react with quinones to form reduction products containing, as a nuclear substituent, sulfur to which is linked a cation, sulfur or a carbon atom, which sulfiding compounds when in the salt form have the cation in the form of a light metal, and especially an alkali metal, or ammonia or an organic amine (for example, addition products of 1,4-naphthoquinone with sodium sulfide, ammonium sulfide, sodium hydrosulfide, and ammonium hydrosulfide).

As disclosed in application Serial No. 450,784, filed August 18, 1954, by Leigh C. Anderson and Chester E. Smith, Jr., the reduction promoting effect upon the reducing action of alkali metal alcoholates on reducible aromatic nitrogen compounds of the type referred to above is also brought about by ortho-cycloalkano-benzoquinoid compounds, such as ortho-cycloalkano-benzoquinones (benzoquinones in which two adjacent carbon atoms of the quinone nucleus other than those forming

part of the carbonyl groups are linked respectively to the end carbon atoms of a chain of at least 3 carbon atoms, and preferably 4 carbon atoms, of which at least 2 are saturated carbon atoms and the others may be unsaturated—whether free from other substituents in the benzene nucleus besides the carbonyl oxygen atoms and the cycloalkano radical, or containing additional substituents in the benzene nucleus wherein one or more of the hydrogen atoms of the benzene nucleus is substituted by another atom or radical); addition compounds of such benzoquinones, e. g., with hydroquinones, bisulfites, heavy metal salts, sulfiding compounds, etc.; functional derivatives and tautomeric forms of such benzoquinones capable of isomerizing to such benzoquinones, e. g., imides, oximes, semicarbazones and hydrazones; and hydroquinones corresponding to such benzoquinones (for example, 2,3-cyclopropano-1,4-benzoquinone, 2,3-cyclobutano-1,4-benzoquinone, 2,3-cyclobutano-benzohydroquinone, 6-chloro-2,3-cyclobutano-1,4-benzoquinone, 2,3-cyclobuteno-1,4-benzoquinone, 2,3-cyclobutano-1,4-benzo-hydroquinone diacetate, 2,3-(2'-chloro-cyclobuteno)-1,4-benzoquinone).

And, as disclosed in application Serial No. 448,378, filed of even date herewith, by A. V. Erkkila, effective reduction promoting influence upon the reducing action of alkali metal alcoholates on reducible aromatic nitrogen compounds of the type referred to above is produced by certain condensed polynuclear dioxy compounds (diketones, hydroxy-ketones, addition compounds thereof—such as with the bisulfites disclosed in my Patent No. 2,645,636—functional derivatives, and tautomeric forms thereof capable of isomerizing thereto, and corresponding dihydroxy compounds in which the keto groups are replaced by

groups) which contain at least 10 nuclear carbon atoms; namely, those in which one of the nuclei consists of a 6-carbon atom alicyclic dioxy radical having the oxy substituents in quinoid relation to each other, at least 2 of the nuclear carbon atoms of said dioxy radical other than those bearing the oxy substituents being saturated carbon atoms (for example, condensed polynuclear derivatives of cyclohexandiones, cyclohexendiones, cyclohexandiols and cyclohexendiols, having the oxy groups in 1,2- or 1,4-relation, such as 1,2- and 1,4-dioxy-naphthalenes and especially 1,4-naphthandiones and 1,4-naphthandiols). Specific illustrative examples of compounds of said type are: $\Delta^{5,7,8a}$ -naphthoquinone-1,4-dione, $\Delta^{2,6}$ -naphthoquinone-1,4-dione, Δ^6 -naphthoquinone-1,4-dione, 2,3-dichloro- $\Delta^{5,7,8a}$ -naphthoquinone-1,4-dione, 2,3-epoxy- $\Delta^{5,7,8a}$ -naphthoquinone-1,4-dione, 5,8-endomethylene- $\Delta^{2,6}$ -naphthoquinone-1,4-dione.

Thus, the expression "naphthoquinoid reduction promoter" as employed herein, including the claims, denotes and includes all of the foregoing naphthoquinones, derivatives and related compounds.

In the practice of the preferred embodiment of the present invention, the aromatic nitrogen compound is subjected to the reducing action of a mixture of a reducing sugar and a caustic alkali, preferably dextrose and sodium hydroxide, dissolved or suspended in a suitable reaction medium, such as water, a water-miscible solvent, or an aqueous solution of such solvent, to which one or a plurality of naphthoquinoid reduction promoters also have been added or otherwise incorporated, preferably in small amount.

According to the preferred procedure, one of the reactants (the caustic alkali, the reducing sugar, the aromatic nitrogen compound, or the promoter) is added gradually to a mixture of the other reactants. For example, the naphthoquinoid reduction promoter, the aromatic nitrogen compound to be reduced and the caustic alkali (or reducing sugar) are preferably mixed with water, a water-miscible solvent, or an aqueous solution

of the solvent, and the reducing sugar (or caustic alkali) is added in small portions to the resulting mixture. (Addition of the caustic alkali to the other reactants leads to a slightly higher yield of reduction product; addition of the reducing sugar to the other reactants is simpler.) This procedure makes possible, in a simple and effective manner, control of the strongly exothermic reaction, which is an advantage in commercial scale operation.

Various reducing sugars can be employed in the practice of the present invention. Thus, suitable reducing sugars include glycol aldehyde, glycerol aldehyde, erythrose, arabinose, xylose, fructose, invert sugar, galactose, and dextrose (glucose). Dextrose is preferred in view of its efficiency, ready availability, and low cost.

The process of the present invention can be carried out in an aqueous medium under ordinary temperatures and pressures, but the reduction usually does not proceed as energetically nor to as low a stage of oxidation as when the reduction reaction medium comprises a water-miscible organic solvent, such as a monohydric alcohol containing 1 to 3 carbon atoms and preferably methanol. When a water-miscible solvent is employed it may be employed as such or in the form of an aqueous solution. The amount of water and/or water-miscible solvent employed is preferably at least sufficient to dissolve the caustic alkali and provide a readily stirrable reaction mixture. In general, the efficiency with which the reduction is promoted increases with an increase in the concentration of the water-miscible solvent in the mixture. Accordingly, in commercial practice it is preferable to employ a reduction medium containing at least about 50% by weight of methanol or other water-miscible solvent, based on the content of said solvent and water in said medium.

The amount of caustic alkali employed is preferably such as to render the reaction mixture strongly alkaline (for example, corresponding with a pH value greater than 12). The concentration of caustic alkali in the reaction medium (water and/or solvent) may vary widely and is preferably between 5% and 50% by weight of the sum of the caustic alkali and solvent therefor (water and/or organic solvent).

The amount of reducing sugar employed is adjusted according to the extent of reduction desired. I have found that a much smaller amount of reducing sugar is usually required to effect a particular reduction than is necessary in the absence of the reduction promoter, as is illustrated in the specific examples below. Thus, as little as one-fourth of the amount of reducing sugar which would be required theoretically to reduce the aromatic nitrogen compound, based on the assumption that only the aldehyde (or keto) group of the reducing sugar is oxidized in the reaction, suffices to accomplish the reduction in Example 4.

The reduction promoter can be incorporated in the reaction medium in various ways and at various times. Usually the reduction promoter is employed as such in forming the reaction mixture. If desired, it may be formed in the reaction mixture or in one of the components thereof; for example, the sodium bisulfite addition product of 1,4-naphthoquinone can be preliminarily formed by reacting the naphthoquinone and bisulfite in water or in methanol, and the resulting mixture can be employed in forming the reaction medium for the reduction, similarly to the procedure disclosed in my Patent No. 2,645,636.

The reduction promoter can be employed in various amounts. It is a feature of the present invention that even small amounts of the naphthoquinoid reduction promoters are effective in bringing about the reduction reaction. The minimum amount necessary to produce a significant reduction-promoting effect varies with the individual naphthoquinoid compound, nature of the aromatic nitrogen compound to be reduced, nature of the reducing sugar, and the reaction conditions. Thus, concentrations ranging in proportions from about $\frac{1}{150}$ mol to about

$\frac{1}{25}$ mol of naphthoquinoid compound, per mol of aromatic nitrogen compound, are usually employed. Generally, the promoter effect is enhanced by increasing the proportion of naphthoquinoid compound employed and is lessened by reducing the proportion of naphthoquinoid compound employed. Ordinarily, amounts greater than about $\frac{1}{10}$ mol of naphthoquinoid compound per mol of aromatic nitrogen compound to be reduced are not advantageous, although they may be used if desired, since the increased cost of the extra naphthoquinoid compound is not sufficiently compensated by the additional benefits derived therefrom to be of commercial importance.

The temperature at which the reaction is carried out may vary widely, and is preferably between room temperature (about 30°) and 100° C., both inclusive. At lower temperatures the reaction is slower and requires costly cooling, while higher temperatures may require the use of closed vessels and/or promote the formation of relatively large amounts of primary amines or other by-products.

The process of the present invention is generally applicable to the reduction of various aromatic nitrogen compounds containing nitrogen as a substituent of a benzene nucleus at a higher stage of oxidation than the hydrazo stage, and especially water-insoluble (particularly, unsulfonated) compounds of this class, such as nitrobenzene, 4-chloro-nitrobenzene, 4-nitrotoluene, 4-nitroanisole, 2-nitro-benzoic acid, 4-nitro-benzoic acid, 2-nitrobenzene sulfonic acid, 2,5-dimethyl-nitrobenzene, 3,3'-dimethylazoxybenzene, 4,4'-dichloro-azoxybenzene and azoxybenzene-4,4'-dicarboxylic acid. The process of the present invention is particularly of value in view of the extensive use of hydrazobenzene and its derivatives, especially those substituted in ortho and meta positions with respect to the hydrazo group, as intermediates for the manufacture of benzidine and related derivatives of benzidine, especially those containing a halogen atom or an alkyl or alkoxy radical as a nuclear substituent; since it provides an improved method for manufacturing hydrazo compounds from the corresponding reducible aromatic nitrogen compounds, such as nitrobenzene, o- and m-nitrotoluenes, 2-nitroanisole, 2-nitrophenetole, 2,2'-azoxytoluene, 2,2'-azoxyanisole, azobenzene, 2,2'-azotoluene, 2,2'-azoanisole, etc., and especially such azoxy and azo compounds.

The process of the present invention is particularly advantageous for reducing 2-halogen nitrobenzenes (e. g., 2-chloro-nitrobenzene and 2,5-dichloro-nitrobenzene) and especially reduction products thereof (e. g., 2,2'-dichloro-azoxybenzene and 2,2'-dichloro-azobenzene), since it permits a more efficient reduction of such compounds to be obtained and produces less by-products resulting from replacement of the labile halogen atoms by OH and OCH_3 groups than the processes employing alkali metal alcohohates; the use of reducing sugars enables the reduction to be carried out more rapidly and at lower temperatures, thereby minimizing side reactions with said halogen atoms.

The invention will be illustrated by the following specific examples, but it is to be understood that it is not limited to the details thereof and that changes may be made without departing from the scope of the invention. The temperatures are in degrees centigrade and the parts are by weight, unless designated as parts by volume in which case the amount signifies the volume occupied by the same number of parts by weight of water at 4° C.

EXAMPLE 1

Part A.—75 parts of dextrose ("Cerelose") were added during about an hour to a warm (55–60°) mixture of 78.5 parts of 2-chloro-nitrobenzene, 135 parts of 50° Bé. aqueous sodium hydroxide, 180 parts of water, and 1 part of 2,3-dichloro-1,4-naphthoquinone while stirring. The resulting mass was heated with stirring to 95–100° and held there for 5 hours. The reaction mixture was then

steam distilled to remove the 2-chloro-aniline formed (about 10% of the theoretical amount), and the residue was allowed to cool to solidify the oil as grains. The grains were filtered off, washed with hot dilute hydrochloric acid and then with water, and dried over calcium chloride in an oven at about 100°.

The resulting product consisted of 2,2'-dichloroazoxybenzene mixed with a considerable amount of 2,2'-dichloro-azobenzene (it had a setting point of 46°) and amounted to 56.5 parts, which corresponds to more than 85% of the theoretical yield of combined dichloro-azoxy- and dichloro-azobenzenes, based on the 2-chloro-nitrobenzene charged.

Part B.—The procedure of Part A of this example was repeated without the addition of 2,3-dichloro-1,4-naphthoquinone. The product consisted essentially of 2,2'-dichloroazoxybenzene (it had a setting point of 54°). It weighed 54 parts, which corresponds to 81% of the theoretical yield of 2,2'-dichloro-azoxybenzene.

EXAMPLE 2

Part A.—Forty parts of dextrose were added with stirring during about 1 hour to a warm (45–50°) mixture of 66.8 parts of 2,2'-dichloro-azoxybenzene, 35 parts of flaked sodium hydroxide, 200 parts of methanol and 2 parts of 2,3-dichloro-1,4-naphthoquinone, and the resulting mixture was further agitated at 45–50° for 20 hours. The mass was then diluted with water to 500 parts by volume and filtered, and the filter cake was washed, first with 100 parts of 10% aqueous hydrochloric acid and then with cold water, and dried.

The product thus obtained consisted essentially of 2,2'-dichloro-hydrazobenzene (it had a melting point of 86–87°) and amounted to 54 parts, which corresponds to 85% of the theoretical yield based on the dichloro-azoxybenzene charged. In addition, some 2-chloro-aniline was formed (about 14% of the theoretical yield).

Part B.—When the procedure of Part A of this example was repeated without addition of 2,3-dichloro-1,4-naphthoquinone, 56 parts of dry product were obtained. It consisted of 46% by weight of 2,2'-dichloro-hydrazobenzene (corresponding to 41% of the theoretical yield) and 54% by weight of a mixture of 2,2'-dichloro-azoxy- and -azobenzenes. In addition, some 2-chloroaniline (about 11% of the theoretical yield) was formed.

EXAMPLE 3

The procedure of Example 2, Part A, was repeated except that the mixture was heated at 45–50° for 2 hours instead of 20 hours. Also, to determine the effect of various amounts of the naphthoquinoid promoter, the procedure was repeated using the amounts of 2,3-dichloro-1,4-naphthoquinone (DCNQ) set out in Table 1. The weight of dry product and percent of theoretical yields of hydrazo compound and 2-chloro-aniline obtained, based on the dichloro-azoxybenzene charged, are set out in Table 1, which shows that the yield of hydrazo compound increased as the proportion of naphthoquinoid promoter was raised.

Table 1

DCNQ, parts	Dry Filter Cake		2,2'-Dichloro- hydrazoben- zene, Percent theory	2-Chloroaniline, Percent theory
	Parts	Percent hydrazo ¹		
0 (control)	60	38.2	36.2	6.5
0.5	57	60	53.9	14.8
1.0	57.5	67.5	61.3	9.3
2.0	57	73.5	66.2	8.1

¹ The hydrazo content was determined by rearrangement to 3,3'-dichloro-benzidine and titration of the latter with nitrous acid. The remainder of the filter cake was a mixture of 2,2'-dichloro-azoxybenzene and 2,2'-dichloro-azobenzene.

EXAMPLE 4

Part A.—Thirty-eight parts of dextrose were added to

a warm (45-50°) mixture of 49.5 parts of azoxybenzene, 33 parts of sodium hydroxide flakes, 220 parts of methanol, and 2 parts of 2,3-dichloro-1,4-naphthoquinone, and the resulting mixture was stirred at 45-50°. The reaction was substantially complete in 3 hours (as indicated by production of a white solid) but was left stirring overnight. The mass was then drowned in 1000 parts of cold water. The resulting precipitate was separated as a cake by filtration, washed with cold water, and dried.

The white product thus obtained consisted essentially of hydrazobenzene (it melted at 126°) and weighed 44.5 parts, which corresponds to 98% of the theoretical yield of hydrazobenzene, based on the azoxybenzene charged.

Part B.—The procedure of Part A of this example was repeated without the addition of 2,3-dichloro-1,4-naphthoquinone. The product obtained as filter cake consisted of azobenzene and some hydrazobenzene, besides unreduced azoxybenzene. It weighed 39.5 parts and had the following composition:

Azobenzene 18.9 parts (41.5% of theory)
Hydrazobenzene 4.5 parts (11.4% of theory)
Azoxybenzene 16.1 parts (32.5% recovery).

EXAMPLE 5

Forty parts of dextrose were added during 2 hours to a well stirred warm (45-50°) mixture of 400 parts of methanol, 50 parts of sodium hydroxide flakes, 121 parts of 2,2'-dimethoxy-azobenzene, and 2 parts of 2,3-dichloro-1,4-naphthoquinone. The resulting mixture was agitated about 16 hours at 45-50° to complete the reduction, then diluted with 900 parts of water to precipitate the hydrazo compound, and filtered. The filter cake was well washed with water and air dried.

The dried product was essentially 2,2'-dimethoxyhydrazobenzene and weighed 122 parts, which substantially corresponds to the theoretical yield of 2,2'-dimethoxyhydrazobenzene based on the 2,2'-dimethoxy-azobenzene charged.

EXAMPLE 6

Part A.—Fifty-five parts of sodium hydroxide flakes were added during about 11 hours to a well stirred mixture, maintained at 40-45°, of 385 parts of methanol, 70 parts of dextrose, 4 parts of 2,3-dichloro-1,4-naphthoquinone, and 133.6 parts of 2,2'-dichloro-azoxybenzene (in the form of a filter-cake containing about 10% of moisture). The resulting mixture was further stirred at 40-45° for about 13 hours, then diluted with water to a volume of 1000 parts and filtered. The filter cake was thoroughly washed with water and air dried. The dry product thus obtained was essentially 2,2'-dichloro-hydrazobenzene (it melted at 86-87°) and weighed 116 parts, which corresponds to a yield of 92% of the theoretical based on the dichlor-azoxybenzene charged.

Part B.—The procedure of Part A of this example was repeated except that the dextrose, rather than the sodium hydroxide flakes, was added to the mixture of the other reactants. The yield of 2,2'-dichloro-hydrazobenzene obtained was about 86% of the theoretical (109 parts of product melting at 86-87°).

Part C.—The procedure of Part A of this example was repeated except that the azoxy compound was added to the mixture of the other reactants. The product weighed 122 parts and was composed of 75% by weight of 2,2'-dichloro-hydrazobenzene and 25% by weight of a mixture of 2,2'-dichloro-azobenzene and 2,2'-di-chloro-azoxybenzene (it melted at 80-83°).

The process of the present invention is also of special advantage in connection with the manufacture of 2,2'-dialkoxy-hydrazobenzenes from 2-chloro-nitrobenzene. An economical and efficient process involves reacting 2-chloro-nitrobenzene with caustic alkali and a lower alcohol (specifically sodium hydroxide and methanol) in an excess of the alcohol as solvent, whereby the corresponding 2-alkoxy-nitrobenzene (specifically o-nitroani-

sole) is formed; adding a small amount of a naphthoquinoid reduction promoter (e. g. 2,3-dichloro-1,4-naphthoquinone) and additional alcohol and caustic alkali (e. g. methanol and sodium hydroxide) to the resulting reaction mixture and stirring the mixture (with gentle warming if necessary) until formation of the corresponding dialkoxy-azoxybenzene and/or dialkoxy-azobenzene is completed; and then adding a reducing sugar (specifically dextrose) in sufficient amount to complete the reduction of the azoxy and/or azo compounds to the corresponding ortho-dialkoxyhydrazobenzene and continuing the reaction until said reduction is complete.

This procedure, which is illustrated in the following example, has the advantage that a high yield of hydrazobenzene compound can be obtained, with relatively low yield of primary amine by-products, by means of reducing agents much less costly than the zinc and caustic alkali formerly employed and without requiring a costly separation of zinc oxide from the product.

EXAMPLE 7

Part A.—Three hundred and fifteen parts of 2-chloro-1-nitrobenzene were added to a solution of 128 parts of sodium hydroxide flakes in 520 parts of methanol. The mixture was stirred for about 22 hours, during which the temperature was gradually raised from 40° to about 65°, to complete formation of o-nitroanisole (2-methoxy-nitrobenzene).

Part B.—160 parts of methanol and 4 parts of 2,3-dichloro-1,4-naphthoquinone were added to the mixture thus obtained, after which 150 parts of sodium hydroxide flakes were introduced during about 4 hours while stirring and maintaining the temperature at 55-60° with cooling. The reaction mixture was then stirred at 55-60° for 16 hours to form 2,2'-dimethoxy-azobenzene together with some 2,2'-dimethoxy-azoxybenzene.

Part C.—To the reaction mixture thus obtained 150 parts of dextrose were added during about 4 hours while stirring and maintaining the temperature at 45-50°. This resulted in complete reduction to 2,2'-dimethoxyhydrazobenzene. The reaction mixture thus obtained was steam distilled to remove the methanol, diluted with 450 parts of hot water, then cooled to 30°, and filtered. The filter cake was washed alkali-free with water. When dried, a sample melted at 102°. A yield of 77% of the theoretical yield of 3,3'-dimethoxybenzidine hydrochloride, based on the 2-chloro-1-nitrobenzene charged, was obtained by rearranging the filter cake of hydrazo compound thus obtained, with acid in the known manner.

As above noted, the invention is not limited to the details of the foregoing illustrative examples and changes may be made without departing from the scope of the invention.

Thus, other aromatic nitrogen compounds containing nitrogen in a reducible form as a substituent in a benzene nucleus, and especially those at a lower stage of oxidation than the nitro stage, can be substituted in place of the specific compounds subjected to reduction in the foregoing specific examples; for example, nitrobenzene, o-nitrotoluene, m-nitrotoluene, m-nitrochlorobenzene, p-nitrophenetole, p-nitrobenzoic acid, and reduction products thereof, especially, 2,2'-azoxytoluene, 3,3'-azoxytoluene, 3,3'-dichloroazoxybenzene and 4,4'-azoxy-dibenzoic acid and their corresponding azo compounds can be substituted.

Further, it is possible to carry the reduction of a particular reducible aromatic nitrogen compound to other stages than that of a particular specific example, depending on the nature and amount of reducing sugar, caustic alkali and naphthoquinoid promoter employed and the particular reaction conditions, such as concentration of water-miscible solvent, temperature, etc. Thus, it is possible to reduce a nitrobenzene to a hydrazobenzene in a single reaction mixture; however, it is also possible to reduce the nitro compound to the azoxy and/or azo

compound in one reaction mixture, isolate the azoxy and/or azo compound and then reduce it further with a fresh charge of reactants in a separate reaction mixture.

While the nitrogen compound is not reduced to any substantial degree by the alcohol under the preferred conditions herein employed (since the reducing sugar is a more vigorous reducing agent in the presence of caustic alkali than the alcohol, as evidenced by the fact that when the procedure of Example 2, Part A, was repeated without the dextrose substantially no reduction occurred and 66 parts of 2,2'-dichloro-azoxybenzene were recovered), the invention includes a procedure and reaction conditions where the alcohol also functions as an auxiliary reducing agent; as for example, when carrying out the process for prolonged reaction periods at elevated temperatures and in concentrated alcoholic reaction media.

The products of the reduction can be isolated from the reaction mixtures in any suitable manner. Aside from those cases in which the reaction mixture contains an insoluble residue resulting from the presence of the reduction promoter in the reaction mixture, the isolation of the reduction products can be carried out in the usual manner. For example, the reaction mixture may be cooled to solidify or crystallize the reduction product and filtered, and the filter cake washed with water. In those cases where the product is molten and insoluble in the hot mixture, the mixture can be stratified into an aqueous phase and an oil phase, which can be readily separated as illustrated in the examples. When a solvent such as methanol is employed, it is preferable to remove the solvent by steam distillation prior to separation of the product from the mass. When the use of the reduction promoter produces a small amount of insoluble by-product, it may be removed by filtering the hot mixture prior to the phase-separation, or in other suitable manner.

I claim:

1. The improvement in the method of reducing an aromatic nitrogen compound containing nitrogen in a reducible form as a substituent of a benzene nucleus at a higher stage of oxidation than the hydrazo stage by reacting the aromatic nitrogen compound with a reducing sugar and a caustic alkali, which comprises carrying out the reduction in a reaction medium in which a naphthoquinoid reduction promoter has been incorporated, whereby the reduction of the aromatic nitrogen compound is promoted.

2. The improvement in the method defined in claim 1, wherein the naphthoquinoid reduction promoter is a 1,4-naphthoquinoid compound.

3. The improvement in the method of effecting the alkaline reduction of an aromatic nitrogen compound containing nitrogen in a reducible form as a substituent of a benzene nucleus at a stage of oxidation higher than the hydrazo stage and lower than the nitro stage, which comprises reacting the aromatic nitrogen compound with a reducing sugar and a caustic alkali in a reaction medium containing a water-miscible organic solvent and in which a naphthoquinoid reduction promoter has been incorporated.

4. The improvement in the method defined in claim 3, wherein the solvent is a monohydric alcohol having 1 to 3 carbon atoms.

5. The improvement in the method defined in claim 4, wherein the solvent is methanol.

6. The improvement in the method defined in claim 5, wherein the reducing sugar is dextrose, the caustic alkali is sodium hydroxide, and the reaction mixture is maintained at a temperature between 30 and 100° C.

7. The improvement in the method of effecting the alkaline reduction of a water-insoluble aromatic nitrogen compound containing nitrogen in a reducible form as a substituent of a benzene nucleus at a higher stage of oxidation than the hydrazo stage, which comprises reacting the aromatic nitrogen compound with dextrose and sodium hydroxide in a reaction medium which contains a water-

miscible organic solvent and in which a 1,4-naphthoquinoid compound has been incorporated in small amount.

8. The improvement in the method of effecting the alkaline reduction of an aromatic nitrogen compound selected from the group consisting of nitrobenzene, its ortho-methyl, halogen, methoxy, ethoxy, carboxy and sulfo derivatives, and their reduction products in which the nitrogen is at a higher stage of oxidation than the hydrazo stage, which comprises mixing together methanol, sodium hydroxide, the reducible aromatic nitrogen compound, and a naphthoquinoid reduction promoter in an aqueous medium, and adding a reducing sugar to the resulting reaction mixture while maintaining the temperature between 30 and 100° C.

9. The improvement in the method of effecting the alkaline reduction of an aromatic nitrogen compound selected from the group consisting of nitrobenzene, its ortho-methyl, halogen, methoxy, ethoxy, carboxy and sulfo derivatives, and their reduction products in which the nitrogen is at a higher stage of oxidation than the hydrazo stage, which comprises mixing together methanol, a reducing sugar, the reducible aromatic nitrogen compound, and a naphthoquinoid reduction promoter in an aqueous medium, and adding sodium hydroxide to the resulting reaction mixture while maintaining the temperature between 30 and 100° C.

10. The improvement in the method of effecting the alkaline reduction of an aromatic nitrogen compound containing nitrogen in a reducible form as a substituent of a benzene nucleus at a higher stage of oxidation than the hydrazo stage and having a labile halogen substituent, which comprises reacting the aromatic nitrogen compound with a reducing sugar and sodium hydroxide in a reaction medium in which a naphthoquinoid reduction promoter has been incorporated.

11. The improvement in the method of effecting the alkaline reduction of an aromatic nitrogen compound containing nitrogen in a reducible form as a substituent of a benzene nucleus at a stage of oxidation higher than the hydrazo stage and lower than the nitro stage and having a labile chloro nuclear substituent, which comprises reacting the aromatic nitrogen compound with sodium hydroxide and dextrose in a reaction medium which contains a monohydric alcohol having 1 to 3 carbon atoms and in which a naphthoquinoid reduction promoter has been incorporated in small amount.

12. The improvement in the method defined in claim 11, wherein the alcohol is methanol and the naphthoquinoid reduction promoter is a 1,4-naphthoquinone.

13. The improvement in the method of reducing an aromatic nitrogen compound containing nitrogen in a reducible form as a substituent of a benzene nucleus at a higher stage of oxidation than the hydrazo stage, but not higher than the azoxy stage, by reacting the aromatic nitrogen compound with a reducing sugar and a caustic alkali, which comprises carrying out the reduction in a reaction medium comprising a water-miscible organic solvent.

14. The improvement in the method defined in claim 13, wherein the aromatic nitrogen compound is an azobenzene and the solvent is a monohydric alcohol having 1 to 3 carbon atoms.

15. The improvement in the method defined in claim 14, wherein the solvent is methanol.

16. The method of producing 2,2'-dialkoxy-hydrozo-benzenes which comprises reacting 2-chloro-nitrobenzene with a lower alcohol and caustic alkali to form the corresponding 2-alkoxy-nitrobenzene, adding to the resulting reaction mixture a naphthoquinoid reduction promoter and reducing the alkoxy-nitrobenzene to at least the corresponding dialkoxy-azoxybenzene stage in said reaction mixture by means of alcohol and caustic alkali, and then carrying the reduction further to the corresponding dialkoxy-hydrazobenzene in said reaction mixture by means of a reducing sugar and caustic alkali.

13

17. The method of producing 2,2'-dimethoxy-hydrazobenzene defined in claim 16, wherein the alcohol is methanol, the caustic alkali is sodium hydroxide and the reducing sugar is dextrose.

18. The improvement in the method defined in claim 5 3, wherein the reducing sugar is dextrose, the caustic alkali is sodium hydroxide, the solvent is methanol, and the naphthoquinoid reduction promoter is a 1,4-naphthoquinoid compound.

19. The improvement in the method defined in claim 10

14

18, wherein the naphthoquinoid reduction promoter is 2,3-dichloro-1,4-naphthoquinone.
